UNITED STATES PATENT OFFICE.

JOHN E. SCOTT, OF PHILADELPHIA, PENNSYLVANIA, ASSIGNOR OF ONE-HALF
TO CHARLES E. JONES, GUARDIAN OF CHARLES R. HALL, OF SAME PLACE.

TOY.

SPECIFICATION forming part of Letters Patent No. 415,176, dated November 12, 1889.

Application filed August 14, 1889. Serial No. 320,737. (No model.)

To all whom it may concern:

Be it known that I, JOHN E. SCOTT, a citizen of the United States, residing at Philadelphia, in the county of Philadelphia and State of Pennsylvania, have invented a new and useful Improvement in Toys, of which the following is a specification.

The invention relates to an improvement in toys; and it consists of a circular disk formed of card-board and constructed concave upon its upper surface, and surrounded by an upwardly-projecting wall or border. The upper surface of the disk is divided into four equal compartments by partitions that extend across it at right angles to each other, terminating with and attached to the inner surface of the surrounding border. Each of the subdivisions formed by said partitions is subdivided into concentric channels by walls that extend perpendicularly, and whose lower edges are attached to the upper surface of the concave base. These walls have each a passage or opening in one end, alternating with each other in each subdivision, that permit of the passage or traversing of a sphere (when placed in the outer channel) to the center of the apparatus, or in a reverse direction when placed at the center, as the apparatus is manipulated by inclining its concave surface, as will be more fully understood from the following description.

In the accompanying drawings, which make a part of this specification, Figure 1 represents a plan or surface view of the toy. Fig. 2 is a vertical section taken through the line *a a* of Fig. 1. Fig. 3 is a like view taken through the line *b b* of Fig. 1.

Like letters in all the figures indicate the same parts.

The toy, for cheapness of material and construction, I propose manufacturing of paper card-board, the base or bottom *A* being stamped between dies or other suitable mechanism into the shape of an inverted cone, so as to form the lowest point of the upper surface *d* at the center. This base *A* is surrounded by a wall *B*, also of card-board, extending upward vertically, its lower edge being united to the periphery of the base *A*. Within the

circumferential wall *B* are arranged a series of four subdividing-walls *D*, that radiate from the center of the apparatus at right angles to each other, and whose outer ends form contact with the inner surface of the circumferential inclosing-wall *B*, thus dividing the apparatus into four equal compartments. Each of these compartments *E* has a series of upwardly-projecting walls *G*, equidistant from each other and secured upon their lower edges to the upper surface of the base *A*, thus forming the segmental concentric channels *L*.

N are passage-ways or openings—one upon each wall *G*—arranged alternately with each other, that permit of the passage of the balls *T* through the channels from the circumference of the apparatus to the center, or vice versa, as desired.

The mode of operation is as follows: A series of four balls is used in the performance of the game, one being placed in each compartment at the center, if desired, they being separated from each other by the subdividing-walls *D*, which cross each other at that point. Then the apparatus is so manipulated by moving or tilting from a level position as to cause the spheres to traverse through the circuitous channels *L* and passages *N* to the outer channel at the intersection of the walls *G* with walls *D*, or to be returned again to the center by a vice-versa operation, if desired.

I claim as my invention—

The apparatus herein described, consisting of the base *A*, having a concave surface *d* and having a circumferential inclosing-wall *B*, said surface *d* being subdivided into compartments by means of the walls *D*, said compartments being divided into concentric channels *L* by means of the concentric walls *G*, having openings *N* arranged alternately in the ends of said walls *G*, and the balls *T*, substantially in the manner herein shown and described.

JOHN E. SCOTT.
